Primary Examiner — Austin Murphy

(57) **CLAIM**

The ornamental design for a VR head strap, as shown and described.

DESCRIPTION

1. VR head strap

1.1 : Perspective

1.2 : Perspective

1.3 : Front

1.4 : Back

1.5 : Left

1.6 : Right

1.7 : Top

1.8 : Bottom

1.9 : Enlarged

The parts shown by means of broken lines in the reproductions are not part of the claimed design; FIG. 1.9 is the enlarged view of the portion taken at line 1.9 in FIG. 1.1; the dash dot dash broken lines in the reproductions represent boundaries for the enlarged view and form no part of the claimed design.
